Specification of Letters Patent.

Patented Dec. 5, 1916.

Application filed May 25, 1908. Serial No. 434,769.

To all whom it may concern:

Be it known that we, SAMUEL G. DORMAN and JOHN H. MAGNUS, citizens of the United States, residing at Poplar Bluff, Missouri, have invented a new and useful Recording-Machine, of which the following is a specification.

This invention relates to recording machines, and, more particularly, to adding and recording machines; and in such general and specific classes of machines the present invention relates to mechanism for controlling and operating the paper carriage in its lateral movements to present 10 different positions or columns on the paper at the recording position.

The broad object of the invention is to produce a novel and efficient mechanism in machines of the classes referred to for controlling the paper carriage in its lateral 20 movements.

Another object is to produce, in combination with recording mechanism, automatic mechanism for moving the paper laterally 25 the width of a column space or other predetermined distance after any record is made.

A further object is to produce, in combination with mechanism for recording two or more characters side by side without moving 30 the paper, mechanism for automatically moving the paper laterally.

Another object is to produce, in combination with adding and recording mechanism and the controlling means thereof, automatic means for moving the paper laterally 35 after any number or total is recorded.

Certain adding and recording machines, such, for instance, as that shown and described in the patent to Hubert Hopkins, No. 1,039,130, dated September 24, 1912, and in British patent to Hopkins, No. 854, of 40 1904, comprise a laterally-movable paper carriage or platen, a plurality of type-carriers operable side by side to record numbers 45 containing two or more characters at one operation of the controlling mechanism or handle, and adding mechanism operable to add the numbers recorded.

The present invention relates to such class 50 of machines and another object of the invention, therefore, is to produce such a ma-

chine having mechanism whereby the paper carriage or platen will be automatically moved or shifted laterally and stopped in suitable position so that the numbers may be recorded in different columns. This mechanism is subject to control or adjustment so that it may be rendered inoperative or inactive at any time to permit the numbers to be recorded in the same vertical 55 column. 60

Other objects and advantages of the invention will appear from the following description, reference being made to the accompanying drawings, in which—

Figure 1 is a vertical longitudinal sectional view of a machine of the type shown in the aforesaid Hopkins Patent No. 1,039,130, and in the said British Patent No. 854, of 1904, embodying the present invention. Fig. 2 illustrates the present invention in detail, the remaining parts of the machine being omitted from this view to avoid confusion. Fig. 3 is an enlarged detail view of the lever and its connections whereby the carriage releasing mechanism 70 is actuated. Fig. 4 is a perspective view of the adjusting lever or key whereby the releasing mechanism is thrown into, or out of, operative position, as desired. Fig. 5 is a view of the carriage stop mechanism or 75 escapement. Fig. 6 is a plan view of the carriage and the bar with which the escapement members engage. Fig. 7 is a rear elevation of the carriage stop mechanism. Fig. 8 is an end view of the carriage showing the 80 automatic mechanism for turning the platen 85 to move the paper for line spacing, the platen shaft being in section along the line 8—8 of Fig. 6. Fig. 9 is a sectional view of the carriage or platen mechanism taken on the line e—e of Fig. 6. Fig. 10 is a detail view of part of the type-carrier stop mechanism.

The machine illustrated, which is one class of machines with which this invention 95 is to be used, comprises a platen 1 mounted in a laterally-movable carriage 2; said carriage being movably held on a carriage support 3. A series of type-carriers 4 are movable to record on paper held on the platen. 100 These type-carriers in the present instance

are in the form of sectors swinging from a shaft 4^a, and may be operated to record a single character, or two or more characters side by side at a single operation of the operating or controlling means. The controlling means in the type of machine illustrated, as fully described in the said Hopkins Patent, No. 1,539,130, comprises a main shaft 5, held and moved to idle position after each operation by one or more springs 6 and, through its connections (not herein illustrated) also controlling the type-carriers. A handle 7 affords means for rocking the shaft to permit operation of the type-carriers. It is sufficient for present purposes, to state that when the handle 7 is drawn forward, as shown in dotted lines, the type-carriers will move to recording position as illustrated in dotted lines in Fig. 1, and produce the desired record on the paper on the platen. Essential parts of said machine include a series of keys 100, preferably ten in number, whose levers are pivoted intermediate of their front and rear ends, and which are provided with terminals 101 at their rear ends. A carriage 102 is supported on wheels 103 which are mounted on track members 104 and is actuated leftward relative to the operator by a shaft 105 which has a gear segment 106 meshing with a rack 107 on the carriage. Normally depressed pins 108 are in the carriage, said pins being in longitudinal rows, the row at the left relative to the operator being above the terminals of the key levers 100 when the machine is at rest. Operation of a key pushes up the pin corresponding thereto in the carriage, one of which is shown in Fig. 10. As soon as the key is released the carriage is automatically moved one step leftward (the mechanism for which operation is immaterial in this instance), and by successive operations of the keys the desired number or matter is set up and becomes represented in the carriage. A series of parts 109 coöperate with the type-carriers 4, and, when the type-carriers are moved forward, projections 110 on the parts 109 strike against the pins 108 that had been elevated and thereby stop the type-carriers in proper position to align the desired type along the printing line. At the proper time, hammers 111 are thrown against the type, by means of springs 112, thereby driving the type to print. Automatic means is provided in such machine to restore the type-carriers, the parts 109, the carriage 102, the pins 108 and other operated parts to idle position after each operation. Such parts are known in said Hopkins machine and, therefore, require no further description here, it being sufficient to assume and know that the parts do operate in substantially this manner.

At each end of the platen shaft a ratchet wheel 8 is attached. To the ends of the platen carriage two levers 9 are pivoted, said levers extending vertically rearward from the platen shaft, and each of said levers having a pawl 10 pivoted to its upper end. Said pawls 10 ride upon the ratchet wheels 8 so that if the levers 9 be oscillated rearward and forward the pawls, by engaging with the teeth of the ratchet wheels, will rotate the platen thereby feeding the paper thereon for line spacing. A feed roller 11 operating against the lower side of the platen coöperates therewith to hold the paper. A lever 12 is suspended at each end of the platen shaft, and a rod 13 is carried by the lower ends of said levers. Links 14 connect the levers 12 with the levers 9 so that oscillation of the levers 12 will cause the pawls 10 to rotate the platen. In the Hopkins machine and in the machine of the British patent referred to automatic means is provided whereby the rod 13, and thereby the levers 12, will be oscillated effectively to rotate the platen as required to feed the paper vertically one line space after each record is made. Said automatic means, as shown, includes a link or lever 90 (Fig. 1) having one end engaging the rod 13, and being pivotally supported at its opposite end; together with a link 91 having one end connected to the link or lever 90 and arranged to be oscillated or reciprocated forwardly and backwardly effectively to cause the pawls 10 to rotate the platen and feed the paper in line spacing at each operation of the type-carriers. Each of the pawls 10 has a pin 15 extending over an adjacent lever 16 whereby said pawls may be raised out of engagement with the ratchet wheels. The levers 16 are attached to a rock shaft 17 so that both levers are necessarily operated together. A plate 18 is pivoted adjacent to one of the levers 16 and has a notch 19 (Fig. 6) wherein the adjacent lever 16 may be engaged and held when it is desired to prevent rotation of the platen after each operation of the handle. These devices, in one form or another, are embodied in the said Hopkins machine, and the machine of the British Patent #854, of 1904 and the present invention comprises mechanism to be used in, and form part of, such machine.

A motor 20, of any well known type, or a spring of the retractile type if desired, is used to actuate the platen carriage leftward relative to the operator facing the machine. A rod or shaft 21 is supported in bearings on the carriage support 3. A lever 22 is attached to said rod or shaft, extending vertically, and its upper end being actuated against a cross-bar 23 constituting part of the platen carriage by a spring 22^a. A series of notches 24, separated about the distance of a column space, are formed in the bar 23, and in these notches the lever 22 engages to hold the carriage in position to receive 13

records in any column of the paper. That is, by moving the platen and carriage to the extreme right relative to the operator, the recording devices will record in the column at the left of the paper, the paper being moved vertically one line space by the automatic devices above described. Thus a complete list of items may be recorded in that column, after which the platen may be moved leftward and the next column presented to receive records, the lever 22 holding the carriage by engaging in the column-space notches 24. On occasions, however, it is desired to record the items in lines running across the paper, and mechanism is included in this invention automatically to position the carriage for the next record or item after one item has been recorded. In such cases the platen-rotating pawls 10 are rendered inoperative by holding them out of engagement with the ratchet wheels 8, through the medium of the plate 18, as above described. A lever 25 is pivotally supported at 26. A lever 27 is pivotally supported at 28, and the upper end thereof is behind a lateral projection 29 on the lower end of the lever 22, so that forward movement of the upper end of the lever 27 will release the lever 22 from the notch in the bar 23 and permit the motor 20 to draw the platen leftward. An oblique slot 30 at the lower end of the lever 27 receives a pin 31 on the rear end of the lever 25. It is obvious, therefore, that if the lever 25 be oscillated by raising its forward end the lever 22 will be disengaged from the carriage and said carriage will be moved by its motor. A plate or dog 32 swings from a pivot pin 33 at the front end of the lever 25 and is prevented from backward swinging by a pin 34 thereon engaging against a shoulder 35 on said lever 25. As shown in Fig. 1 of these drawings, and also in the drawings of the Hopkins application above identified, the springs 6 connect to levers 36 on the shaft 5 and said levers swing forward whenever the handle 7 is drawn forward. A projection 37 on one of said levers 36, when moved forward, rubs against the dog 32, swinging the latter forward until the said projection 37 passes below said dog 32. When the levers 36 and other parts start back to idle position the projection 37 abuts against the lower end of the dog 32 and raises the front end of the lever 25. This action, obviously, results in releasing the lever 22 from the platen carriage which is thereupon moved by its motor. The movement of the levers 36 is rapid and, since the lower end of the dog 32 is restrained from backward movement, the projection 37 quickly moves from under the end of the dog 32, thereby releasing it. The spring 22 then acts to throw the upper end of the lever 22 against the bar 23 in time to engage in

the next notch 24, thereby stopping the platen in position to present the next column space on the paper for record.

A support 50 rearward from the platen carriage upholds a pivoted lever 51 which projects under the rear edge of the bar 23. A link 52 connects a cam 53 which is rigid on the main shaft 5 with a lever 54 which is pivoted to the support 50. A roll 55 is carried by the lever 54 and projects under the rear end of the lever 51. A spring 56 connects the rear end of the lever 51 with a stationary part and tends to lift up the front end of said lever. When the operating lever 7 is drawn forward the lever 54 will be drawn downward, and the spring 56 will raise the forward end of said lever 51 against the lower side of the bar 23. When the lever 22 is released from the bar 23 the carriage starts toward its new position, and if there were nothing to stop the carriage it might move entirely across the machine—which would happen if the lever 22 should, in any way, be held out of engagement with said bar 23. As soon as one of the notches 24 comes over the end of the lever 51 the latter will be raised into said notch and hold the carriage from further movement until released therefrom by the lever 54 returning to idle position. But before this occurs the projection 37 has released the lever 25 and the lever 22 is pressing against the bar 23 and will snap into the next column space notch 24 which comes opposite the end thereof. In this way the carriage is prevented from moving more than one column space at each operation of the recording devices, and accurate adjustment is assured, the levers 22 and 51 making alternate engagements with the bar 23 as escapement members.

Means is provided to prevent operation of the carriage release in any desired instance. A lever 38 is pivotally supported at its lower end, its upper end extending through a slot 39 in the key-board plate 40, and is connected by means of a link 41 with the end of the dog 32 above its pivot. The connection of the link 41 and the dog 32 comprises a pin 42 extending through a slot 43 in the link, thereby allowing the dog certain free movement. However, the lever 38 has sufficient movement to cause the link 41 to throw and hold the lower end of the dog 32 forward beyond the reach of the projection 37 when the latter travels forward and backward. This leaves the lever 32 in engagement with the carriage and permits the platen to stand without lateral movement. The lever 38 may be held in its different adjustments in any preferred manner, such as by a projection 44 thereon to engage against shoulders 45 at the side of the slot 39.

It is obvious that there may be various embodiments of this invention, and various

modifications thereof without in the least departing from the spirit and scope of the invention. We do not, therefore, restrict ourselves to any particular embodiment or arrangement, but

What we claim and desire to secure by Letters Patent is:

1. The combination with a paper carriage movable to different lateral positions, means for moving said paper carriage to its different lateral positions, and devices for holding said paper carriage in its different lateral positions, of a shaft, means for actuating said shaft, connections operated by said shaft for releasing said holding means to enable said carriage to be moved laterally, and a device adjustable to hold said connections in position to enable said shaft to operate independently of any operation of said connections.
2. The combination with a laterally movable paper carriage, and means for holding said paper carriage in different lateral positions, of a shaft, means for actuating said shaft, devices operated by said shaft for releasing said holding means to enable said carriage to be moved laterally, an optionally operable device for moving a part of said connections to position so that said shaft may operate independently of any operation of said connections, and means for holding said optionally operable device in position to hold said part of said connections in position to enable said shaft to operate independently thereof as aforesaid.
3. The combination with a paper carriage movable to different lateral positions, means for holding said carriage in its different lateral positions, and paper feed mechanism mounted in said carriage, of a shaft, means for actuating said shaft, means controlled by said shaft for operating said paper feed mechanism in any position of said carriage, means for preventing effective operation of said paper feed mechanism, connections operated by said shaft for releasing said holding means to enable said carriage to be moved laterally, an optionally operable device movable to position to prevent operation of said connections by said shaft, and means for holding said optionally operable device in position to prevent operation of said connections by said shaft.
4. The combination with a paper carriage, a bar in said carriage, shoulders on said bar, and an actuator for moving said carriage laterally, of a lever, means for moving said lever into engagement with said shoulders to stop lateral movement of said carriage, means for disengaging said lever from said shoulders, and a second lever arranged to engage with said shoulders to hold said carriage in its different lateral positions.
5. In a machine of the character described, the combination with a laterally movable paper carriage, devices for holding said carriage in its different lateral positions, and a motor device for moving said carriage, of a shaft, connections operated by said shaft to release said holding devices to enable said paper carriage to be moved laterally, means for moving a part of said connections to an inoperative position, and a device for holding said connection inoperative.
6. In a recording machine, the combination with a laterally movable paper carriage, means for moving said paper carriage laterally, and means for holding said paper carriage, of a shaft, means for rocking said shaft, connections operated by said shaft for releasing said holding means to enable said carriage to be moved laterally, a manipulative device for moving a part of said connections to position so that said shaft may operate independently of any operation of said connections, and means for holding said manipulative device in position to hold said connections inoperative.
7. In an adding machine, the combination with a laterally movable paper carriage, means for holding said paper carriage in various adjustments, and means for moving said paper carriage laterally, of a shaft, lever connections for releasing said holding means from said carriage, a device actuated by said shaft effectively to operate said lever connections, a manipulative element for moving said device to position in which said shaft may operate independently thereof, and means for holding said element in position to hold said device in the position aforesaid, substantially as described.
8. In an adding machine, the combination with a laterally movable paper carriage, devices for holding said carriage in its different lateral positions, and a motor device for moving said carriage to its different lateral positions, of a shaft, connections for releasing said devices from said carriage to enable said motor to move said carriage laterally, means for holding said connections in position to be operated by said shaft or not, as desired, and means for reengaging said holding devices with said carriage, substantially as described.
9. In an adding machine, the combination with a laterally movable paper carriage, and a motor for moving said carriage laterally, of a shouldered bar in said carriage, an element arranged to cooperate with said bar to stop said carriage, a lever arranged to engage the shoulders on said bar to hold said carriage in its different lateral positions, a rock shaft, means operated by said rock shaft for disengaging said lever from said bar, and independent means for reengaging said lever with said bar, substantially as described.
10. In an adding machine, the combination with a laterally movable paper carriage, devices for holding said carriage in its different lateral positions, and a motor device for moving said carriage to its different lateral positions, of a shaft, connections for releasing said devices from said carriage to enable said motor to move said carriage laterally, means for holding said connections in position to be operated by said shaft or not, as desired, and means for reengaging said holding devices with said carriage, substantially as described.

riage, a motor for moving said carriage laterally; a shouldered bar in said carriage, a lever, and a spring for holding said lever in engagement with the shoulders on said bar, of a rock shaft, a lever, a plate pivoted to said second-named lever, means on said rock shaft for engaging said plate to actuate said second-named lever, means actuated by said second-named lever for disengaging said first-named lever from said bar to enable said motor to move said carriage, substantially as described.

11. In an adding machine, the combination with a laterally movable paper carriage, a motor for moving said carriage, a device for holding said carriage in its different lateral positions, a rock shaft, and levers on said rock shaft, of a lever supported independently of said rock shaft, a member pivoted on said lever, means for holding said member in or out of position to be actuated by said levers on said rock shaft, as desired, and means controlled by said second-named lever for releasing said holding device from said carriage, substantially as described.

12. In an adding machine, the combination with a laterally movable paper carriage, a motor for moving said carriage laterally, a device for stopping said carriage, and releasable mechanism for holding said carriage in its different lateral positions, of a rock shaft, means for releasing said mechanism by operation of said rock shaft to permit said motor to move said carriage, and optionally adjustable means for preventing said rock shaft from releasing said mechanism.

13. In an adding machine, the combination with a laterally movable paper carriage, a motor for moving said carriage laterally, a device for stopping said carriage in different lateral positions, and re-

leasable mechanism for holding said carriage in different lateral positions, of a rock shaft, means controlled by said rock shaft for releasing said mechanism to permit said motor to move said carriage, mechanism controlled by said rock shaft for controlling said device, means for engaging said device with said carriage as an incident to the operation of said last-named mechanism by said rock shaft, and optionally adjustable means for preventing release of said releasable mechanism by said rock shaft.

14. In an adding machine, the combination with a laterally movable paper carriage, a motor for moving said carriage laterally, and a device operable to stop said carriage, of a rock shaft, mechanism controlled by said rock shaft determining when said device will operate to stop said carriage, releasable mechanism for holding said carriage in different lateral positions and means for releasing said mechanism by said rock shaft.

15. In an adding machine, the combination with a laterally movable paper carriage, a motor for moving said carriage laterally, a device operable to stop said carriage, and a rock shaft determining when said device will operate, of releasable mechanism holding said carriage in different lateral positions, and optional means for releasing said mechanism by said shaft to enable said motor to move said carriage.

In testimony whereof, we hereunto affix our signatures to this specification this 15th day of April, 1908, in the presence of two witnesses.

It is hereby certified that in Letters Patent No. 1,207,147, granted December 5, 1916, upon the application of Samuel G. Dorman and John H. Magnus, of Poplar Bluff, Missouri, for an improvement in "Recording-Machines," an error appears in the printed specification requiring correction as follows: Page 2, line 8, for the patent number "1,539,130" read 1,039,130; and that the said Letters Patent should be read with this correction therein that the same may conform to the record of the case in the Patent Office.

Signed and sealed this 2d day of January, A. D., 1917.

[SEAL.]

R. F. WILHELM BARD,

Acting Commissioner of Patents.
